INSECT ELECTROCUTING TRAP

Allan W. Houghton, 1116 S. Alfred St., Alexandria, Va.

Filed May 10, 1960, Ser. No. 60,517

Term of patent 14 years

(Cl. D31—3)

Fig. 1.

Fig. 2.

Fig. 1 is a front elevational view of an insect electrocuting trap embodying my new design, the rear being substantially the same;

Fig. 2 is a top plan view thereof;

Fig. 3 is a left side elevational view thereof, the right side not shown being substantially the same as the left side shown; and

Fig. 4 is a fragmentary vertical cross-sectional view thereof, taken substantially in the plane of the line 4-4 of Fig. 3 with the outside grill broken away for sake of clarity.

I claim:

The ornamental design for an insect electrocuting trap, as shown and described.
